Primary Examiner — Susan E Krakower*Assistant Examiner* — Roselynne Cody(74) *Attorney, Agent, or Firm* — R. William Graham(57) **CLAIM**

The ornamental design for a sanding sponge holder, as shown and described.

DESCRIPTION

FIG. 1 is a top front left side perspective view of a sanding sponge holder showing our new design with the sanding sponge in place. The portion of the sanding sponge, shown in broken lines, forms no part of the claim;

FIG. 2 is a top front left side perspective view of a sanding sponge holder without the sanding sponge;

FIG. 3 is a top front right side perspective view thereof;

FIG. 4 is a bottom view thereof;

FIG. 5 is a rear elevation view thereof;

FIG. 6 is a top view thereof;

FIG. 7 is a front elevational view thereof; and,

FIG. 8 is a right side elevation view thereof, the left side being a mirror image.
